ALKYLATION OF POLYNUCLEAR AROMATIC HYDROCARBONS

Robert J. Moore, Berkeley, Calif., assignor to
Shell Development Company, San Francisco,
Calif., a corporation of Delaware

Application March 29, 1948, Serial No. 17,708

16 Claims. (Cl. 260—671)

1
This invention relates to an improved process for the more efficient production of alkyl substituted derivatives of polynuclear aromatic hydrocarbons. It relates more particularly to an improved method for alkylating polynuclear hydrocarbons having condensed aromatic nuclei with olefinic hydrocarbons.

Because of the characteristics and properties peculiar to them, the alkyl substituted derivatives of polynuclear aromatic hydrocarbons in relatively pure state are of prime importance. Their value resides not only in their utility as such in many important fields of application, but in their usefulness as a starting or intermediate material in the production of a wealth of chemical derivatives. High viscosity index values and excellent oxidation stability render certain alkyl derivatives of polynuclear aromatic hydrocarbons of well-defined structure, such as, for example, the alkyl naphthalenes of particular value as components of high quality lubricants. This is especially true of the polynuclear aromatic compounds having one or more long alkyl side chains with a minimum of branching. Dicetylnaphthalene, for example, has a viscosity in the SAE range of 30 and a viscosity index of about 118.

Realization of the advantages inherent in the large scale utilization of the alkyl substituted polynuclear aromatic hydrocarbons in relatively pure state heretofore generally has been impossible due to the lack of a practical source of such materials. Available sources comprised, for example, processes primarily directed to the production of products other than the alkyl substituted polynuclear aromatic hydrocarbons in which these materials are produced in relatively minor amounts as a by-product. Separation of the desired compounds in a relatively high state of purity from such complex mixtures containing them generally entailed the use of additional costly steps militating against practical utilization of a product thus obtained. Processes have been disclosed directed to the alkylation of aromatic hydrocarbons with olefins. Such processes, however, though enabling the relatively efficient production of certain alkyl substituted mono-nuclear aromatic hydrocarbons are unsuited to the efficient production of a product consisting essentially, or predominantly, of alkyl substituted polynuclear aromatic hydrocarbons of specific structure or composition. The production of any alkyl substituted polynuclear aromatic compounds in such processes is generally not only accompanied by low yields, extremely short catalyst life, and operational difficulties themselves

often precluding practical operation of the process, but is furthermore unavoidably limited to the production of a product comprising these desired compounds as a minor proportion of a highly complex mixture from which they are separable only by resort to additional costly procedure. Consequently attempts to make use of the highly advantageous properties peculiar to the alkyl substituted polynuclear aromatic hydrocarbons on a practical scale heretofore generally has been limited to the utilization of the available highly complex fractions, or mixtures, comprising uncontrolled and often minor amounts of such compounds of widely varying structures.

2
15 It is an object of the present invention to bring within the realm of practicability the more efficient production of alkyl substituted polynuclear hydrocarbons having aromatic nuclei.

A further object of the invention is the provision of an improved process for the more efficient production of products consisting essentially, or predominantly, of alkyl substituted polynuclear aromatic compounds of specific composition.

20 Still another object of the invention is the provision of an improved process for the more efficient production of alkyl substituted polynuclear aromatic compounds having one or more long side chains with a minimum of branching directly connected to a nuclear carbon atom.

25 A more particular object of the invention is the provision of an improved process for the more efficient production of alkyl substituted naphthalenes. Other objects and advantages of the invention will become apparent from the following detailed description thereof.

In accordance with the invention a polynuclear aromatic hydrocarbon is contacted with an olefin in a reaction zone in the presence of a molar excess of a mono-nuclear aromatic hydrocarbon and an aliphatic hydrocarbon-aluminum halide complex which has been saturated with a mono-nuclear aromatic hydrocarbon prior to introduction into the reaction zone, at alkylating conditions effecting the selective alkylation of the polynuclear hydrocarbon in the absence of any substantial alkylation of the mono-nuclear aromatic hydrocarbon. In a preferred method of executing the invention at least a part of the effluence from the reaction zone, comprising an alkyl substituted polynuclear hydrocarbon and catalyst complex, is introduced into a catalyst displacing zone. Within the catalyst displacing zone the reactor effluence is contacted with an additional quantity of mono-nuclear aromatic

hydrocarbon thereby displacing substantially all polynuclear hydrocarbons from the catalyst, resulting in the formation of a product phase comprising polynuclear hydrocarbons substantially free of catalyst and a catalyst phase substantially free of polynuclear hydrocarbons. At least a part of the catalyst phase comprising catalyst complex in admixture with mono-nuclear aromatic hydrocarbon is withdrawn from the catalyst displacing zone and passed to the reaction zone. The product phase is passed from the catalyst displacing zone to a product separating zone.

Polynuclear aromatic hydrocarbons selectively alkylated in accordance with the invention comprise the class of polynuclear aromatic hydrocarbons containing at least two aromatic nuclei and having a hydrogen atom capable of being replaced by an alkyl group directly connected to a carbon atom in an aromatic nucleus. The aromatic nuclei of the suitable polynuclear aromatic hydrocarbons may contain one or more substituent alkyl groups provided there remains at least one replaceable hydrogen atom on the aromatic ring. Examples of the suitable polynuclear aromatic hydrocarbons selectively alkylated in accordance with the invention are: naphthalene, anthracene, phenanthrene, ace-naphthene, dihydroanthracene, stilbene, fluorene, perylene, picene, diphenyl, their homologues etc. Of the suitable polynuclear aromatic hydrocarbons those having two or more condensed aromatic nuclei are preferred. Particularly preferred are the naphthalene hydrocarbons comprising naphthalene and the suitable alkyl substituted naphthalenes, such as methylnaphthalene, dimethylnaphthalene, trimethylnaphthalene, ethylnaphthalene, diethylnaphthalene, methylethylnaphthalene, propylnaphthalene, isopropylnaphthalene, etc. The use of a polynuclear aromatic hydrocarbon charge comprising a mixture of two or more of the suitable polynuclear aromatic hydrocarbons or of hydrocarbon fractions consisting of, or predominating in, such polynuclear aromatic hydrocarbons is comprised within the scope of the invention.

Mono-olefins suitable as starting materials for the process of the invention comprise the normally gaseous and normally liquid unsaturated hydrocarbons having two or more carbon atoms to the molecule and containing an olefinic bond between two adjacent carbon atoms. Suitable mono-olefins of open chain and cyclic structure comprise, for example, ethylene, propylene, butylene-1, butylene-2, isobutylene, the amylenes as pentene-1, pentene-2, 3-methyl-butene-1, 2-methyl - butene - 1, 2 - methyl - butene - 2, the hexylenes as hexene-1, hexene-2, hexene-3, 3-methyl - pentene - 1, 2 - methyl - pentene - 3, 2 - methyl - pentene - 1, 2 - methyl - pentene - 1, 2 - methyl - pentene - 2, 3 - methyl - pentene - 2, 2,3 - dimethyl - butene - 1 and 2,3 - dimethyl - butene-2, the heptylenes, the octylenes, the nonylenes, the decylenes, undecylenes, cyclopentene, methylcyclopentene, cyclohexene, methylcyclohexene, and their homologues, olefinic polymers, etc. The mono-olefins may be further substituted by the replacement of one or more of the hydrogen atoms by alkyl, or cycloalkyl groups. The particular mono-olefins chosen as charge material will of course be governed by the nature of the product desired. The olefin charge need not necessarily consist of a single mono-olefin, and two or more mono-olefins may be comprised in the charge to the process. The olefin charge may comprise materials other than the mono-

olefins, capable of acting as diluents, temperature or flow controlling means, etc. Such materials which may be included in the olefin charge comprise gases and vapors having no adverse effect upon the execution of the desired reaction, such as, for example, normally gaseous saturated hydrocarbons, nitrogen, carbon dioxide and the like. Suitable olefinic charge material comprises hydrocarbon mixtures or fractions containing substantial amounts of the mono-olefins. Olefinic charge materials particularly preferred because of the relative ease with which they enter into the desired selective alkylation reaction under the conditions of the invention and the desirability of

10 the resulting alkylated products thereby obtained, are the mono-olefins having from five to twenty carbon atoms to the molecule. Of these mono-olefins those of straight chain structure or having a minimum of branching are particularly preferred.

15 In order to set forth more fully the nature of the invention reference will be had, in the following detailed description thereof, to the attached drawing wherein the single figure illustrates one form of apparatus suitable for its execution.

20 A polynuclear aromatic hydrocarbon, such as, for example, naphthalene, taken from any suitable source, is introduced into the reaction zone 30 of the system. Although the naphthalene may be introduced into the reaction zone as such in the solid or molten state, in the preferred method of executing the invention the polynuclear aromatic hydrocarbon is introduced into the reaction zone dissolved in a suitable solvent. The solvent is introduced by means of valved line 10 into a chamber 11 containing a supply of naphthalene. Although any solvent may be employed which does not adversely affect execution of the process,

25 40 it is preferred to let a portion of the mono-nuclear aromatic hydrocarbon stream forming an essential part of the method of the invention as described fully hereinbelow, function simultaneously as the solvent for the naphthalene.

45 Thus the mono-nuclear aromatic hydrocarbon introduced into chamber 11 by means of line 10 may consist in part or entirely of the mono-nuclear aromatic hydrocarbon stream recycled from within the system as described hereinabove.

50 55 The solution of naphthalene in mono-nuclear aromatic hydrocarbon is passed from chamber 11, through valved lines 12 and 13 into the reaction zone. The reaction zone may comprise a suitable reaction chamber such as, for example, a reactor 14 of the mixer type provided with stirring means. Although but one such reactor is shown in the drawing, a plurality of such reactors connected in series or in parallel may be employed.

60 65 The olefinic hydrocarbon charge to the system, for example, 1-pentene is introduced into reactor 14 from an outside source by means of line 16. Essential to the attainment of the objects of the invention is the presence within reactor 14 of a substantial excess of a mono-nuclear aromatic hydrocarbon such as, for example, benzene. The mono-nuclear aromatic hydrocarbon is introduced into reactor 14 by means of line 13.

70 75 Although in the present illustrative description benzene has been chosen as the preferred mono-nuclear aromatic hydrocarbon employed in the process of the invention, any member of the homologous series of mono-nuclear aromatic hydrocarbons may be employed in its stead. Examples of such suitable mono-nuclear aromatic

hydrocarbons are; the alkyl substituted benzenes such as, toluene, xylene, ethylbenzene, methyl-ethylbenzene, isopropylbenzene, diethylbenzene, and their homologs, etc.

Within reactor 14 selective catalytic alkylating conditions are maintained assuring the selective alkylation of the polynuclear aromatic hydrocarbon with the olefin in the absence of any substantial alkylation of the mono-nuclear aromatic hydrocarbon. The selective alkylating conditions within reactor 14 are obtained by the use as catalyst of a preformed aliphatic hydrocarbon-aluminum halide complex which has been saturated with a mono-nuclear aromatic hydrocarbon, such as, for example, benzene, prior to introduction into the reaction zone, and which contains substantially no free aluminum halide, and the maintenance of the reactants and the mono-nuclear aromatic hydrocarbon within the reactor above well-defined minimum proportions.

The aliphatic hydrocarbon-aluminum halide complexes suitable for use in the process of the invention, are obtained by the interaction of an aliphatic hydrocarbon, preferably an olefinic hydrocarbon or an aliphatic hydrocarbon giving rise to an intermediate olefinic reaction product, and an aluminum halide. Of the aluminum halides, aluminum bromide, aluminum chloride and the mixed halides such as AlCl_2F , AlClF_2 , AlBr_2F , etc., are preferred. Aluminum chloride is particularly preferred. The use of a hydrocarbon other than an aliphatic hydrocarbon such as, for example, an aromatic hydrocarbon in the preparation of the complex has been found unsatisfactory.

The catalyst complex may be prepared within the system. To effect this aluminum halide, for example, aluminum chloride, is introduced into a suitable vessel such as chamber 20 provided with suitable stirring means. An aliphatic hydrocarbon, for example, an olefin or an olefin-yielding aliphatic hydrocarbon derivative or compound, such as tertiary butyl chloride, is introduced into chamber 20 by means of valved line 22. The temperature within chamber 20 may be maintained within the range of, for example, from about room temperature to about 150° C. A hydrogen halide, such as hydrogen chloride, is preferably introduced into chamber 20 by means of line 23 leading into line 22, to aid in the complex formation. Within chamber 20 interaction of the aluminum chloride and olefin or olefin-yielding compound takes place to result in the formation of an aluminum chloride-aliphatic hydrocarbon complex which is fluid and oily in appearance. Essential to the attainment of efficient operation of the process is the utilization of a complex which is free of any substantial amount of free aluminum chloride. Sufficient olefin or olefin-yielding aliphatic hydrocarbon or compounds is, therefore, introduced into chamber 20 to assure the production therein of a complex containing no substantial amount of free aluminum chloride. The absence of isomerization activity for paraffin hydrocarbons, such as n-pentane can be used as a convenient test for the absence of free AlCl_3 in this catalyst.

From chamber 20 the complex is passed through line 24 to a suitable separator such as, for example, separating drum 25, wherein any supernatant hydrocarbons are removed from the lower catalyst phase. Essential to the attainment of efficient operation of the process of the invention is the saturation of the complex with a mono-nuclear aromatic hydrocarbon prior to its introduction into the reaction zone. It is preferred

to employ as the mono-nuclear aromatic hydrocarbon for this purpose the same mono-nuclear aromatic material introduced into the reaction zone and employed as solvent for the naphthalene, thereby enhancing the simplicity and flexibility of the process. Accordingly the catalyst phase is passed from separator 25, through line 26, into a catalyst saturating zone. The catalyst saturating zone may comprise any suitable chamber enabling intimate contact of the complex catalyst and the mono-nuclear aromatic hydrocarbon such as, for example, a mixing column 27 provided with suitable baffles, packing, trays or the like. Within column 27 the catalyst complex is brought into contact with benzene introduced into the column by means of line 28. Benzene is introduced into column 27 in an amount at least sufficient to assure complete saturation of the complex. Catalyst complex, now fully saturated with benzene and in admixture with any excess benzene present, is passed from column 27 through lines 31 and 32 into reactor 14.

A particularly effective catalyst was prepared by adding five parts of tertiary butyl chloride to two parts of anhydrous aluminum chloride and stirring the mixture at room temperature until hydrogen chloride evolution ceased. The resulting homogeneous complex was then saturated with benzene. One hundred eight grams of benzene was required to saturate completely 112 grams of the complex. Without intending to limit the scope of the invention by any theories advanced herein to set forth more fully the nature of the invention, the effect of the mono-nuclear aromatic hydrocarbon upon the complex is believed to be more than a mere solvent effect and that compound formation between the aliphatic hydrocarbon-aluminum halide complex and the mono-nuclear aromatic hydrocarbon takes place. Generally the freshly prepared complex will absorb about 4 moles of benzene per mol of AlCl_3 in the complex.

The olefin and polynuclear aromatic hydrocarbons are introduced into reactor 14 in controlled amounts to maintain the molar ratio of polynuclear aromatic hydrocarbon to olefin therein above 1. Charging about 1.25 to about 3 mols, more preferably from about 1.5 to about 2.5 mols, of polynuclear aromatic hydrocarbon per mol of olefin to reactor 14 has been found satisfactory. Higher proportions of the polynuclear aromatic hydrocarbon may, however, be employed. The introduction of the mono-nuclear aromatic hydrocarbon, such as benzene, into reactor 14 is controlled to maintain the mol ratio of the mono-nuclear aromatic hydrocarbon to the total of olefin and polynuclear aromatic hydrocarbons above 1. Thus an amount of mono-nuclear aromatic hydrocarbon in the range of from about 1.25 to about 4 mols, and more preferably from about 1.5 to about 3 mols, per mol of polynuclear aromatic hydrocarbon in reactor 14 has been found suitable. Higher proportions of the mono-nuclear aromatic hydrocarbon may, however, be introduced into the reactor 14. Particularly preferred alkylating conditions comprise the maintenance of the olefin, polynuclear aromatic hydrocarbon, and mono-nuclear aromatic hydrocarbon in reactor 14 in the molar ratio of about 1:2:4, respectively.

Maintenance of an amount of benzene-saturated catalyst complex in reactor 14 in the range of from about 10% to about 200%, and preferably from about 25% to about 100%, by weight 75 of the total hydrocarbon content therein has

been found satisfactory. A higher or lower ratio of catalyst to hydrocarbon may be maintained within the reaction zone, however, within the scope of the invention.

The temperature within reactor 14 is maintained in the range of from about 10° C. to about 150° C. and preferably from about 40° C. to about 100° C. Temperature conditions are maintained in reactor 14 by heating means such as, for example, heat exchangers 35 and 36, and optionally by additional temperature controlling means not shown in the drawing. Atmospheric, subatmospheric or superatmospheric pressures may be employed within reactor 14. The use of a superatmospheric pressure sufficiently high to facilitate the flow of reactants through the system is generally preferred. The time of contact will vary in accordance with the specific nature of reactants employed as well as operating conditions such as temperature. In general a contact time of from about one second to about 60 minutes, and preferably from about 5 minutes to about 20 minutes, has been found satisfactory. Higher or lower contact times may, however, be employed within the scope of the invention.

Hydrogen halide is preferably introduced into the reaction zone by means of line 37 leading into line 13. A hydrogen halide, for example, hydrogen chloride, in an amount ranging from about 0.1% to about 1% of the hydrocarbon charge to reactor 14 is generally employed. Higher or lower amounts of the hydrogen halide may, however, be employed, within the scope of the invention.

Under the above-defined conditions the polynuclear aromatic hydrocarbon is selectively alkylated by the olefin in the absence of any substantial alkylation or other modification of the mono-nuclear aromatic hydrocarbon. Thus, in the specific application of the invention here stressed, the naphthalene is selectively alkylated by the pentene to amylnaphthalene in the absence of any substantial alkylation of the benzene, notwithstanding the fact that benzene will undergo alkylation in the absence of the polynuclear aromatic hydrocarbon. It has been found that the selective alkylation furthermore proceeds in the absence of substantial side chain isomerization and without any substantial interaction of catalyst and reactants and absorption of reactants by the catalyst. It is believed that the selective alkylation and concomitant advantages are directly attributable to the specific mono-nuclear aromatic hydrocarbon-saturated complex containing substantially no free aluminum halide, and the presence in molar excess of the mono-nuclear aromatic hydrocarbon.

Effluence from reactor 14 comprising amylnaphthalene, catalyst complex, unreacted naphthalene, benzene, and hydrogen halide, is passed through line 40, provided with suitable heat controlling means, such as a heat exchanger 41, into a separator 42. Within separator 42 a lower catalyst layer is separated from a supernatant hydrocarbon layer. The supernatant hydrocarbon layer is passed from separator 42 through line 43 into accumulator 44.

A part or all of the catalyst layer drawn from separator 42 is recycled through valved lines 46 and 32 to the reaction zone. The catalyst phase thus drawn from separator 42 will generally comprise some alkylated naphthalene. In a preferred method of carrying out the process of the invention at least a part of the catalyst phase withdrawn from separator 42 through line 46 is pref-

erably passed into a catalyst displacing zone such as, for example, a column 48 provided with suitable packing, baffles, trays, or the like. Within column 48 the catalyst phase is contacted counter-currently with benzene introduced through valved line 49. Substantially all remaining alkylated polynuclear aromatic hydrocarbon will be displaced from the catalyst phase. The treatment of the catalyst phase within column 48 is executed at a temperature in the range of, for example, from about 20° C. to about 150° C. It is preferred, however, to effect the treatment of the catalyst phase at a temperature above about 50° C., and preferably in the range of from about 60° C. to about 90° C. Substantially improved separation of product from catalyst, it has been found, is obtained at the higher temperatures. Heat input into column 48 is obtained by heating means, such as a heat exchanger 50 in line 49, and a closed coil 51 in the lower part of column 48. Improved phase separation within separator 42 is obtained by maintaining the separator contents within the range of elevated temperatures prescribed for the treatment within column 48. Catalyst complex substantially free of alkylated polynuclear aromatic products is taken from the base of column 48 and passed, in part or entirety, through valved lines 53 and 54 into line 28 leading into the catalyst saturator 27.

Material comprising the hydrocarbon product is taken from accumulator 44 and passed through line 53 into a stripper 57. Within stripper 57 an overhead fraction comprising the hydrogen chloride promoter is separated from a liquid fraction comprising alkylate, unconverted reactants and benzene. The hydrogen chloride-containing fraction is taken from stripper 57 through valved line 37 and passed into line 13 leading into the reaction zone. Normally gaseous material comprising hydrogen chloride may be flashed from accumulator 44 and passed through line 58 into recycle line 37. A valve outlet 59 is provided to enable the elimination of normally gaseous materials from the system. A part of the hydrogen chloride stream may be diverted from line 37 through line 60 leading into valved lines 26 and 61. Fresh hydrogen chloride is introduced into the system by means of valved line 63.

The liquid fraction is taken from the lower part of stripper 57 and passed through line 65 into a fractionator 66. Overhead from column 48, comprising benzene and amylnaphthalene, is passed through line 64 into line 65. Within fractionator 66 there is separated an overhead fraction comprising any unconverted pentene present, a higher boiling fraction comprising amylnaphthalenes, and an intermediate fraction comprising benzene and unconverted naphthalene. The higher boiling fraction comprising amylnaphthalenes is separated from fractionator 66 through valved line 68 as a final product. The overhead from fractionator 66 may be recycled, in part or entirety, to reactor 14 by means not shown in the drawing. The intermediate fraction separated within fractionator 66 and comprising benzene and unconverted naphthalene is recycled, in part or entirety, through lines 67 and 69 into line 13 leading to the reaction zone.

In a preferred method of carrying out the process of the invention, at least a part of the intermediate fraction taken from fractionator 66 through line 67 is passed through valved line 70 into a fractionator 71. Within fractionator 71 an overhead fraction comprising benzene is separated from liquid bottoms comprising naphtha-

9

lene and benzene. Liquid bottoms are taken from fractionator 71 through valved line 72 and recycled, in part or entirety, through valved lines 69 and 13, to reactor 14.

Overhead comprising benzene is taken from fractionator 71 and recycled through line 10 to drum 11, and into line 17, 28 and 49 as described above. Make-up benzene is introduced into the system from an outside source through valved line 75. The amount of benzene taken overhead in fractionator 71 is generally controlled to provide sufficient recycle benzene to function as the solvent for the polynuclear aromatic hydrocarbon charge, the saturating medium for the catalyst complex, and the displacing medium for the catalyst phase. Sufficient benzene is, however, left in the bottoms of fractionator 71 to assure the efficient recycling of naphthalene to the reaction zone. If desired, an intermediate fraction comprising any by-products boiling between the boiling temperature of the mono-nuclear aromatic solvent and the polynuclear aromatic hydrocarbon may be separated periodically within fractionator 71 and taken therefrom by means of valved line 76.

The process of the invention thus enables the efficient production of alkyl substituted polynuclear aromatic hydrocarbons of specific structure in a high state of purity with a minimum of operative steps. The selectivity of the alkylation, the highly efficient separation of product from catalyst complex, and the continuous utilization of the single substantially unaffected mono-nuclear aromatic hydrocarbon stream for the purposes of attaining the selective reaction condition solution of charge, complex saturation, and catalyst displacement altogether constitute a process which is not only exceedingly economical but unusually flexible and simple in operation.

The following examples are illustrative of the efficiency with which polynuclear aromatic hydrocarbons are alkylated in accordance with the invention:

Example I

An olefin-aluminum chloride complex was prepared by reacting 5 parts of tertiary butyl chloride with 2 parts of anhydrous aluminum chloride. 112.5 g. of the complex thus obtained was saturated with benzene at a temperature of 30° to 40° C. in the presence of added anhydrous HCl. To the resulting benzene-saturated catalyst complex thus obtained there was added slowly with stirring over a period of one hour at a temperature of 30° to 40° C., a mixture containing pentene-1, acenaphthene and benzene in a mol ratio of 0.65:1.26:5.5, respectively. The reaction mixture was separated by stratification at room temperature into a catalyst phase, and the catalyst phase was extracted at a temperature of 70° C. with benzene. Eighty-two per cent of the acenaphthene charged was recovered as acenaphthene and alkyl acenaphthene, and 87% of the pentene charged was recovered as amylnacenaphthene. No substantial benzene alkylation was encountered. The distribution of pentenes in the product was as follows:

	Boiling Point, °C. at 1 mm. Hg	Refractive Index, n_D^{20}	Mol Per Cent on Pentene Charged
Amylnacenaphthene.....	138	1.5810	17.7
Diamylnacenaphthene.....	175	1.5884	5.0
Tetramylnacenaphthene.....	260	.....	64.2

10

Example II

A benzene-saturated olefin-aluminum chloride complex was prepared as described in Example I. To this catalyst there was slowly added with vigorous stirring, at a temperature of from 30° to 40° C., a mixture consisting of pentene-1, naphthalene, and benzene, in a mol ratio of 0.8:1.6:3.25, respectively. Thirty minutes were required to complete the addition of the reactants, and the resulting mixture was stirred for another thirty minutes. The product was separated from the catalyst complex as described in Example I and distilled. Seventy-two per cent of the pentene charged was recovered as amylnaphthalenes, and 88% of the naphthalene charged was accounted for. No amylnaphthalene was found in the product. The amylnaphthalenes obtained consisted of:

	Mol Per cent
20 Amylnaphtha'ene	25.5
Diamylnaphthalene	17.9
Triamyl naphthalene	31.1
Tetraamyl naphthalene	19.5

Example III

To the catalyst which had been used in the operation of Example II there was added a mixture consisting of cetene, naphthalene and benzene in a mol ratio of 0.6:1.2:3.2, respectively, under substantially the same conditions employed in the operation of Example II. Distillation of the product showed that 50% of the cetene charged was converted to cetyl naphthalene (B. P. about 320° C. at 1 mm. Hg pressure, n_D^{20} 1.5223) and 26% to dicetyl naphthalene.

Example IV

A benzene-saturated olefin-aluminum chloride complex was prepared as in Example I. To this catalyst there was added a mixture consisting of propylene trimer (C_6 olefin), methylnaphthalene and benzene in a mol ratio of 1:2:4, respectively, at a temperature in the range of 50 to 70° C. The mixture was maintained in contact with the catalyst complex for an overall contact time of about one hour. The product was separated from the reaction mixture substantially as set forth in Example I. Seventy mol per cent of the propylene trimer charged was recovered as alkylated products 73% of which consisted of nonylmethyl naphthalene and the remainder of which was a material boiling above 420° C.

Example V

A catalyst was prepared by saturating with benzene an olefin-aluminum chloride complex obtained by reacting 2 parts of anhydrous aluminum chloride with 5 parts of propylene trimer (C_6 olefin). To the resulting benzene saturated complex there was added, at a temperature of from 50 to 70° C., a mixture of propylene trimer (C_6 olefin), methylnaphthalene and benzene in a mol ratio of 1:2:4, respectively. After an overall contact time of one hour the product was separated from the reaction mixture substantially as described in Example I. It was found that 50 mol percent of the olefin trimer charged was recovered as alkylated products, 75% by weight of which was nonylmethyl naphthalene and the rest of which was a residual product which had a boiling temperature above 370° C.

For the purpose of comparison the following are given:

11
Example VI

To a well-stirred suspension of 37.5 g. of AlCl_3 in a complex prepared by reacting 5 parts of tertiary butyl chloride with 2 parts of AlCl_3 there was slowly added a mixture consisting of benzene and pentene in a mol ratio of 2:1. The temperature was maintained at 30-40° C., and 30 minutes were required to effect the addition of the charge to the catalyst. This was followed by an additional 30 minutes of stirring. The upper hydrocarbon layer obtained by stratification was washed with water to remove dissolved AlCl_3 . Distillation of the hydrocarbon product showed the following material balance based upon the charge. The catalyst was found to have increased 81.5% in weight.

Per Cent of Benzene Charged		Per Cent of 1-pentene Charged
26.3	Benzene.....	8.7
	Pentene.....	13.8
6.9	Amylbenzene.....	6.4
2.2	Diamylbenzene.....	18.0
2.2	Tetraamylbenzene.....	53.1
62.4	Loss to Catalyst.....	

Example VII

A catalyst was prepared by saturating 11.25 g. of complex prepared by reacting 5 parts tertiary butyl chloride and 2 parts AlCl_3 with benzene in the presence of anhydrous HCl at 30-40° C. To this catalyst was added a mixture of 4 mols of benzene and one mol of 1-pentene over a period of 30 minutes followed by an additional 30 minutes of vigorous stirring at room temperature. On separating the hydrocarbon layer, washing and distilling, the following material balance was obtained based on materials charged. The catalyst was found to have increased only 0.8% in weight.

Per Cent of Benzene Charged		Per Cent of 1-pentene Charged
78.9	Benzene.....	0.0
	Pentene.....	55.8
13.9	Amylbenzene.....	4.1
0.5	Diamylbenzene.....	16.4
1.4	Triamylbenzene.....	16.4
0.8	Pentaamylbenzene (average).....	
4.5	Loss.....	7.3

Of the pentene charged 92.7% was, therefore, recovered as benzene alkylate.

For the purpose of clarity, all apparatus not essential to a complete understanding of the invention such as, for example, pumps, condensers, feed tanks, and auxiliary processing and control equipment have been omitted from the drawing. It is to be understood that the apparatus shown may be modified as apparent to one skilled in the art without departing from the spirit and scope of the invention. For example, although only two fractionators are shown in the drawing, more than two will generally be employed in the execution of the invention on a practical scale.

The invention claimed is:

1. The process for the production of amylnaphthalene which comprises reacting naphthalene in solution in a molar excess of benzene with pentene at a temperature in the range of from about 40° C. to about 100° C., a contact time of from 1 second to about 60 minutes, and a pressure sufficient to maintain at least a substantial part of the reactants in the liquid phase, in the presence of a preformed olefin-aluminum chlo-

ride complex which has been pre-saturated with benzene, said complex containing substantially no free aluminum chloride, thereby selectively alkylating said naphthalene with said pentene to form a product comprising amylnaphthalene in the absence of any substantial benzene alkylation.

2. The process for the production of alkyl substituted naphthalenes consisting essentially of cetyl naphthalene and dicetyl naphthalene which comprises reacting naphthalene with cetene at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said naphthalene, and a preformed olefin-aluminum halide complex which has been pre-saturated with benzene, said complex containing substantially no free aluminum halide, thereby selectively alkylating said naphthalene with said cetene with the formation of a product comprising alkyl substituted naphthalenes consisting essentially of cetyl naphthalene and dicetyl naphthalene in the absence of any substantial alkylation of said benzene.

3. The process for the production of alkyl substituted naphthalene consisting essentially of nonylmethyl naphthalene which comprises reacting methyl naphthalene with an olefin having nine carbon atoms to the molecule at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said methyl naphthalene, and a preformed olefin-aluminum halide complex which has been pre-saturated with benzene, said complex containing substantially no free aluminum halide, thereby selectively alkylating said methyl naphthalene with said olefin with the formation of a product comprising alkyl substituted naphthalene consisting essentially of nonylmethyl naphthalene in the absence of any substantial alkylation of said benzene.

4. The process for the production of alkyl substituted naphthalene which comprises reacting a naphthalene hydrocarbon with an olefin having at least five carbon atoms to the molecule at a temperature of from about 10° C. to about 150° C., a contact time of from 1 second to about 60 minutes, and a pressure sufficient to maintain at least a substantial part of the reactants in the liquid phase, while in the presence of a mono-nuclear aromatic hydrocarbon, present in molar excess with respect to said naphthalene hydrocarbon, and a preformed olefin-aluminum halide complex which has been pre-saturated with a mono-nuclear aromatic hydrocarbon, said complex containing substantially no free aluminum halide, thereby selectively alkylating said naphthalene hydrocarbon with said olefin with the formation of a product comprising alkyl substituted naphthalene in the absence of any substantial alkylation of said mono-nuclear aromatic hydrocarbon.

5. The process for the production of alkyl substituted naphthalene which comprises reacting a naphthalene hydrocarbon with an olefin at a temperature of from about 10° C. to about 150° C., a contact time of from 1 second to about 60 minutes, and a pressure sufficient to maintain at least a substantial part of the reactants in the liquid phase, while in the presence of a mono-

nuclear aromatic hydrocarbon, present in molar excess with respect to said naphthalene hydrocarbon, and a preformed aliphatic hydrocarbon-aluminum halide complex which has been pre-saturated with a mono-nuclear aromatic hydrocarbon, said complex containing substantially no free aluminum halide, thereby selectively alkylating said naphthalene hydrocarbon with said olefin with the formation of a product comprising alkyl substituted naphthalene in the absence of any substantial alkylation of said mono-nuclear aromatic hydrocarbon.

6. The process for the production of an alkyl substituted polynuclear aromatic hydrocarbon having two or more condensed aromatic nuclei which comprises reacting a polynuclear aromatic hydrocarbon having at least two condensed aromatic nuclei with an olefin having at least five carbon atoms to the molecule at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said polynuclear aromatic hydrocarbon, and a preformed olefin-aluminum chloride complex which has been pre-saturated with benzene, said complex containing substantially no free aluminum chloride, thereby alkylating said polynuclear aromatic hydrocarbon with said olefin with the formation of a product comprising alkyl substituted polynuclear aromatic hydrocarbon in the absence of any substantial alkylation of said benzene.

7. The process for the production of an alkyl substituted polynuclear aromatic hydrocarbon having two or more condensed aromatic nuclei which comprises reacting a polynuclear aromatic hydrocarbon having at least two condensed aromatic nuclei with an olefin having at least five carbon atoms to the molecule at a temperature of from about 10° C. to about 150° C., a contact time of from 1 second to about 60 minutes, and a pressure sufficient to maintain at least a substantial part of the reactants in the liquid phase, while in the presence of a mono-nuclear aromatic hydrocarbon, present in molar excess with respect to said polynuclear aromatic hydrocarbon, and a preformed olefin-aluminum halide complex which has been pre-saturated with a mono-nuclear aromatic hydrocarbon, said complex containing substantially no free aluminum halide, thereby alkylating said polynuclear aromatic hydrocarbon with said olefin with the formation of a product comprising alkyl substituted polynuclear aromatic hydrocarbon in the absence of any substantial alkylation of said mono-nuclear aromatic hydrocarbon.

8. The process for the production of an alkyl substituted polynuclear aromatic hydrocarbon having two or more condensed aromatic nuclei which comprises reacting a polynuclear aromatic hydrocarbon having at least two condensed aromatic nuclei with an olefin at a temperature of from about 10° C. to about 150° C. while in the presence of a mono-nuclear aromatic hydrocarbon, present in molar excess with respect to said polynuclear aromatic hydrocarbon, and a pre-formed aliphatic hydrocarbon-aluminum halide complex which has been pre-saturated with a mono-nuclear aromatic hydrocarbon, said complex containing substantially no free aluminum halide, thereby alkylating said polynuclear aromatic hydrocarbon with said olefin with the for-

mation of a product comprising alkyl substituted polynuclear aromatic hydrocarbon in the absence of any substantial alkylation of said mono-nuclear aromatic hydrocarbon.

5. The process for the production of an alkyl substituted polynuclear aromatic hydrocarbon which comprises reacting a polynuclear aromatic hydrocarbon with an olefin having at least five carbon atoms to the molecule at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said polynuclear aromatic hydrocarbon, and a preformed olefin-aluminum halide complex which has been pre-saturated with benzene, said complex containing substantially no free aluminum halide, thereby alkylating said polynuclear aromatic hydrocarbon with said olefin with the formation of a product comprising alkyl substituted polynuclear aromatic hydrocarbon in the absence of any substantial alkylation of said benzene.

10. The process for the production of an alkyl substituted polynuclear aromatic hydrocarbon which comprises reacting a polynuclear aromatic hydrocarbon with an olefin having at least five carbon atoms to the molecule at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said polynuclear hydrocarbon, and a preformed aliphatic hydrocarbon-aluminum halide complex which has been pre-saturated with benzene, said complex containing substantially no free aluminum halide, thereby selectively alkylating said polynuclear aromatic hydrocarbon with said olefin with the formation of a product comprising an alkyl substituted polynuclear aromatic hydrocarbon in the absence of any substantial alkylation of said benzene.

15. The process for the production of an alkyl substituted polynuclear aromatic hydrocarbon which comprises reacting a polynuclear aromatic hydrocarbon with an olefin having at least five carbon atoms to the molecule at a temperature of from about 10° C. to about 150° C., a contact time of from 1 second to about 60 minutes, and a pressure sufficient to maintain at least a substantial part of the reactants in the liquid phase, while in the presence of a mono-nuclear aromatic hydrocarbon, present in molar excess with respect to said polynuclear aromatic hydrocarbon, and a preformed olefin-aluminum halide complex which has been pre-saturated with a mono-nuclear aromatic hydrocarbon, said complex containing substantially no free aluminum halide, thereby alkylating said polynuclear aromatic hydrocarbon with said olefin with the formation of a product comprising alkyl substituted polynuclear aromatic hydrocarbon in the absence of any substantial alkylation of said mono-nuclear aromatic hydrocarbon.

20. The process for the production of an alkyl substituted polynuclear aromatic hydrocarbon which comprises reacting a polynuclear aromatic hydrocarbon with an olefin at a temperature of from about 10° C. to about 150° C. while in the presence of a mono-nuclear aromatic hydrocarbon, present in molar excess with respect to said polynuclear aromatic hydrocarbon, and a pre-

15

formed aliphatic hydrocarbon-aluminum halide complex which has been pre-saturated with a mono-nuclear aromatic hydrocarbon, said complex containing substantially no free aluminum halide, thereby alkylating said polynuclear aromatic hydrocarbon with said olefin with the formation of a product comprising alkyl substituted polynuclear aromatic hydrocarbon in the absence of any substantial alkylation of said mono-nuclear aromatic hydrocarbon.

13. The process for the production of alkyl substituted naphthalene which comprises reacting naphthalene with an olefin at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said naphthalene, and a preformed olefin-aluminum halide complex which has been pre-saturated with benzene, said complex containing substantially no free aluminum halide, thereby selectively alkylating said naphthalene with the formation of alkyl substituted naphthalene in the absence of any substantial alkylation of said benzene, thereafter separating the reaction mixture by stratification into a hydrocarbon layer and a catalyst layer comprising naphthalenes, contacting said catalyst layer with benzene under conditions forming a hydrocarbon phase and a catalyst phase substantially free of naphthalenes, and recycling said catalyst phase to said alkylation reaction.

14. The process for the production of alkyl substituted naphthalene which comprises reacting naphthalene with an olefin at a temperature of from about 10° C. to about 150° C., a contact time of from 1 second to about 60 minutes, and a pressure sufficient to maintain at least a substantial part of the reactants in the liquid phase, while in the presence of benzene, present in molar excess with respect to said naphthalene and a preformed aliphatic hydrocarbon-aluminum halide complex which has been pre-saturated with benzene, said complex containing substantially no free aluminum halide, thereby selectively alkylating said naphthalene with the formation of alkyl substituted naphthalene in the absence of any substantial alkylation of said benzene, thereafter separating the reaction mixture by stratification into a hydrocarbon layer and a catalyst layer comprising naphthalenes, contacting said catalyst layer with benzene under conditions forming a hydrocarbon phase and a catalyst phase substantially free of naphthalenes, and recycling said catalyst phase to said alkylation reaction.

15. The process for the production of an alkyl substituted polynuclear aromatic hydrocarbon having two or more condensed aromatic nuclei which comprises reacting a polynuclear aromatic hydrocarbon having at least two condensed aromatic nuclei with an olefin at a temperature of from about 10° C. to about 150° C., a contact time of from 1 second to about 60 minutes, and a pressure sufficient to maintain at least a substantial part of the reactants in the liquid phase,

16

while in the presence of a mono-nuclear aromatic hydrocarbon, present in molar excess with respect to said polynuclear aromatic hydrocarbon, and a preformed olefin-aluminum halide complex which has been pre-saturated with a mono-nuclear aromatic hydrocarbon, said complex containing substantially no free aluminum halide, thereby selectively alkylating said polynuclear aromatic hydrocarbon with the formation of an alkyl substituted polynuclear aromatic hydrocarbon in the absence of any substantial alkylation of said mono-nuclear aromatic hydrocarbon, thereafter separating the reaction mixture by stratification into a hydrocarbon layer and a catalyst layer comprising polynuclear aromatic hydrocarbons, contacting said catalyst layer with a mono-nuclear aromatic hydrocarbon under conditions forming a hydrocarbon phase and a catalyst phase substantially free of polynuclear aromatic hydrocarbons, and recycling said catalyst phase to said alkylation reaction.

16. The process for the production of an alkyl substituted polynuclear aromatic hydrocarbon which comprises reacting polynuclear aromatic hydrocarbon with an olefin at a temperature of from about 10° C. to about 150° C., a contact time of from 1 second to about 60 minutes, and a pressure sufficient to maintain at least a substantial part of the reactants in the liquid phase, while in the presence of a mono-nuclear aromatic hydrocarbon, present in molar excess with respect to said polynuclear aromatic hydrocarbon, and a preformed aliphatic hydrocarbon-aluminum halide complex which has been pre-saturated with a mono-nuclear aromatic hydrocarbon, said complex containing substantially no free aluminum halide, thereby selectively alkylating said polynuclear aromatic hydrocarbon with the formation of an alkyl substituted polynuclear aromatic hydrocarbon in the absence of any substantial alkylation of said mono-nuclear aromatic hydrocarbon, thereafter separating the reaction mixture by stratification into a hydrocarbon layer and a catalyst layer comprising polynuclear aromatic hydrocarbons, contacting said catalyst layer with a mono-nuclear aromatic hydrocarbon under conditions forming a hydrocarbon phase and a catalyst phase substantially free of polynuclear aromatic hydrocarbons, and recycling said catalyst phase to said alkylation reaction.
